UNITED STATES PATENT OFFICE.

WILLIAM L. CHURCH, OF NEWTON, MASSACHUSETTS.

DAM.

No. 833,506.

Specification of Letters Patent.

Patented Oct. 16, 1906.

Application filed February 6, 1906. Serial No. 299,836

To all whom it may concern:

Be it known that I, WILLIAM L. CHURCH, of Newton, in the county of Middlesex and State of Massachusetts, have invented certain new and useful Improvements in Dams, of which the following is a specification.

My invention relates to dams, it being especially directed to means for preserving the foundations of such structures.

It is customary to provide dams either with a vertical face past which the water falls from the crest or with an inclined apron over and in contact with which it flows. In either case the water strikes the bed of the stream in comparatively close proximity to the adjacent edge of the floor or foundation of the dam, washing it away, and gradually undermining the structure. My invention obviates this difficulty.

In the accompanying drawings, in which similar characters designate like parts throughout the several views, Figure 1 is a transverse vertical section through a dam, showing one embodiment of my invention. Fig. 2 represents an elevation of the dam as seen from the downstream side thereof. Fig. 3 is a view similar to Fig. 1 of a dam of different type.

Referring to Fig. 1, a shell dam is shown, having a floor or foundation 10 resting upon the bed of the stream and an upstream wall or deck 11, extending to a crest 12. At the downstream side of the dam is an apron 13, curved outwardly or convexedly from the edge *a* of the crest to a point *a'*, the curvature being approximately that given by gravity and the head of water above the dam to the fluid stream *S* passing over it. Between the points *a'* and *a''* the apron is inclined

downwardly and outwardly on an approximately straight slope, and from *a''* to its termination at *b* it is curved in a direction reverse to the upper portion—that is, concavely. This lower portion is located at some distance above the foundation. The reverse or concave curvature of the terminal portion of the apron is preferably continued until the surface thereof which supports and guides the fluid stream is substantially horizontal, as shown in Fig. 1. Thereby, and also because of the height of said terminal portion above the dam-foundation, the stream flowing over the apron is deflected and projected from the terminus thereof in a direction which carries it directly away from the downstream face of the dam and prevents it

striking the bed of the stream, except at points so far distant from the dam that the shock and erosive action of the falling water cannot injure or undermine the foundations of the dam.

The height of the terminus *b* of the apron above the dam-foundation is preferably such that the lateral projection of the stream—that is, the distance from the dam of the point *c*, at which it strikes the bed—is the maximum. I have found that the maximum projection occurs when the height of the terminus *b* is half that of the crest of the dam above the bed from which it rises, and accordingly I prefer to locate the level of *b* approximately midway between those of the base and crest.

When the terminal portion of the apron is horizontal and is located at a height equal to half that of the crest and the minimum possible flow of water is passing, the water strikes the bed at a distance equal to the entire height of the dam from the base thereof, friction being disregarded. When the head of water over the dam is increased so as to increase the velocity of flow over the crest, this distance is made greater, as it is also when the apron-terminus is elevated by continuing the concave curvature to a point above the horizontal, as in Fig. 3. The trajectory of the stream is then elevated and its length increased. On the other hand, the stream projection may be lessened by changing the level of the apron-terminus from that above specified or depressing the inclination thereof.

Preferably the slope of the rectilinear part of the apron is made to coincide as nearly as possible with the path of the fluid stream under greatest normal head, so that friction is eliminated as completely as possible, while at the same time the stream is caused to flow in contact with the apron over its entire slope.

I have shown this invention in connection with a shell or cellular dam, such as shown in prior Letters Patent No. 768,717, granted August 30, 1904, in which the deck, crest, and apron are supported by walls 14 intermediate the ends of the dam; but it is obvious that the invention is not so limited, since it may equally well be practiced in connection with dams of solid masonry or of any other construction.

I claim—

1. A dam comprising a crest, and an apron terminating in a portion located intermediate

ate the crest and base, and constructed to deflect water flowing over the dam to a point removed from the base.

2. A dam having an apron terminating in a concavedly-curved portion located at a height intermediate the base and crest of the dam, such as to deflect and project the water flowing thereover wholly free of the dam, before striking the bed on which the dam-foun-
10 dation is built.

3. A dam having an apron terminating in a concavedly-curved portion located at a height intermediate the base and crest of the dam, such as to deflect and project the water flowing thereover, a distance not less than the total height of the dam from the foundation thereof, before striking the bed on which the foundation is built.

4. A dam having an apron terminating at a height from the base approximately half that of the crest of the dam, and having its
20

surface adjacent the terminus inclined away from the slope of the apron, whereby water flowing over the dam is deflected away therefrom, and caused to strike the bed of the ²⁵ overflow wholly clear of the dam-foun-
dation.

5. A dam having an apron terminating at a height from the base approximately half that of the crest of the dam, and having its ³⁰ slope adjacent the terminus curved into a substantially horizontal direction, whereby water flowing over the dam is deflected, and caused to strike the bed of the overflow at a distance not less than the total height of the ³⁵ dam from the dam-foundation.

In testimony whereof I have affixed my signature in presence of two witnesses.

WILLIAM L. CHURCH.
